PERMANENT MAGNET ASSEMBLY FOR
ELECTRODYNAMIC LOUD-SPEAKERSFred J. Harbaugh, Haddonfield, N. J., assignor to
Radio Corporation of America, a corporation
of Delaware

Application November 30, 1945, Serial No. 632,065

4 Claims. (Cl. 179—115.5)

1

This invention relates to sound transducers and more particularly to a permanent magnet dynamic loudspeaker.

An object of the invention is to provide a new and improved method and means of assembly of magnetic elements of a loudspeaker.

More particularly it is an object of the invention to provide improved and simplified means for holding the elements of a permanent magnet loudspeaker together in desired operating relation.

Still other objects and advantages of the invention will be apparent from the following specification. The features of novelty which I believe to be characteristic of the invention are set forth with particularity in the appended claims. The invention itself, however, both as to its fundamental principles and as to its particular embodiments will best be understood by reference to the specification and accompanying drawings in which:

Figure 1 is a cross sectional view in side elevation of a loudspeaker magnet structure, etc. embodying the invention.

Figures 2 and 3 are side elevation fragmentary views, partly in section, of a loudspeaker magnet system embodying modified forms of the invention.

Figure 4 is a side elevation view in section of a loudspeaker magnet system embodying a modified form of the invention.

Figure 4a is a plan view, reduced in size, of an element shown in Figure 4, and

Figures 5 and 6 are fragmentary views partly in section, reduced in size, of modifications embodying the invention.

In the various figures like reference numerals represent like parts.

Referring now more particularly to Figure 1, the invention is illustrated by means of a speaker unit adapted for use with a horn of the exponential type, not shown. A paramagnetic field structure comprising a cup-shaped field yoke 1 of ferromagnetic material such as cold rolled steel or other paramagnetic material is provided with an annular pole piece or yoke plate 3 of similar material fastened to the open end of the field yoke 1 by means of machine screws 5 or projection welding. Centrally located within the yoke 1 is a permanent magnet 7 of high retentivity preferably "Alnico," composed of the following elements, aluminum, nickel, cobalt, and iron. This magnetic material is extremely hard, cannot be drilled or tapped, at least by ordinary means, and is molded in short lengths. The upper and lower pole faces of the magnet 7 are ground flat and lie in parallel planes. In this modification, the magnet 7 is provided with a central bore functioning as part of the horn. The base of the magnet rests upon a pole face or ground flat surface of the bottom of the yoke 1 the bore being in alignment with a similar

2

opening 9 in the bottom of the cup. A soft iron or mild steel inner pole piece 11 is located upon the pole face or top surface of magnet 7 and the upper end of this pole piece cooperates with a circular opening in yoke plate 3 in forming an annular air gap.

For the purpose of accurately centering the pole piece 11 with respect to the opening 13 a sheet metal centering disc 15, preferably of spring bronze or brass, is permanently secured to the yoke plate 3 as by rivets 14 or welding and is provided with a circular opening concentrically disposed with respect to opening 13 in the yoke plate. This centering disc is formed with a downward bias tendency as indicated by the dotted line 15'. To improve the spring action the central portion of the disc is preferably divided into independently acting segments, in the manner disclosed in connection with Figure 4a. In the position shown, the spring tension exerted downwardly by the disc 15 forces the pole piece 11 downwardly against the magnet 7 and maintains good magnetic contact and holds the magnetic elements 11, 7 and 1 together in assembled relation. Ordinarily, friction resulting from the pressure exerted by disc 15 is sufficient to prevent displacement of magnet 7 laterally relative to elements 1 and 11, but to insure against undue displacement caused by dropping the unit, limiting means shown in Figures 4, 5 and 6 may be used. The periphery of the base of the magnet 7 may be welded to the yoke 1 if desired.

The unit may be assembled as follows: The magnet 7 can be located in the position shown and the pole piece 11 placed on top thereof as indicated. Next, the yoke plate 3 can be dropped into approximately the position shown and clamping pressure applied to force it downward against the pressure exerted by the disc 15 onto the ends of the cup-like yoke member 1 into the position indicated, the screws 5 being then tightened to maintain the assembled position. Welding may be used to hold these members together, particularly in case a U-shape open type yoke member is used, as shown in Figure 4. During this operation the pole piece 11 will slide a little one way or the other on top of the magnet 7, the annular air gap at 13 being accurately maintained by means of the disc 15 which functions both as a centering disc and resilient clamping plate for holding the magnet elements in assembled operating position.

A voice coil 17 is wound upon a cylindrical form 19 the top end of which is closed by a diaphragm 21. The voice coil structure is flexibly supported for vibratory movement by means of a concentrically corrugated centering disc 23 of fibrous material supported at its periphery by a ring 25, the latter being secured to the yoke 3 in any desired manner. It will be apparent to those skilled in the art that the type of magnet 7 and hollow pole piece 11, provided with central openings for

the horn, cannot be bolted to the yoke 1 in the usual manner. This novel arrangement solves the difficulty.

Referring to the modification in Figure 2, the magnet 7 is centrally located upon the base of a U-shape yoke as in Figures 4 and 5, and is preferably held in position as shown in these figures, described below. The pole piece 27 is located on the top of magnet 7 and is provided with a laterally extending flange 29. The yoke plate 3 is located upon the open end of yoke 1 in the same manner as shown in Figure 1. The pole piece 27 is centered within the opening 13 of plate 3 by means of a relatively stiff centering disc 16, preferably of brass or phosphor-bronze, fastened permanently to plate 3. A plurality of brass screws 31 are threaded in the disc 16 and extend upwardly through holes in plate 3 for turning to force the flange 29 downwardly against magnet 7, the clamping exerted axially by these screws and resiliency of the disc retaining the magnetic elements in assembled relation. The assembly of parts is easy in this case and requires no special tools. The parts may be taken apart readily. The centering disc and screws, in other words, are retaining means for both centering and clamping the magnetic members.

Referring to Figure 3, the parts are assembled as in Figure 2 with the exception that the non-magnetic centering disc 33 is used solely to align the pole piece 35 and to accurately maintain an annular air gap. The screws 31 are threaded in the yoke plate 3, but extend through clearance holes in disc 33 to maintain a clamping action as in Figure 2. The pole piece 35 is provided with a flange or shoulder of magnetically permeable material and preferably integral therewith, against which the screws exert pressure. A cup-shape element 33, as of brass, is inverted over the flange 37, under the screw ends, the lip extending downward around the top of the magnet to limit lateral shifting of the latter. In this modification the magnet 37 and pole piece are of the usual solid type, used with a conventional frusto-conical type diaphragm 39. During assembly of the magnet 34 laterally into position, the screws 31, elements 37 and 38 are raised sufficiently to clear the top of the magnet.

Referring to Figure 4, I have illustrated the invention in connection with a magnet system similar to that shown in Gaubert et al. Patent 1,991,738 of February 19, 1935, and it may be considered in the nature of an improvement thereover. In the Gaubert et al. patent the magnetic elements including a cobalt steel block magnet are held in assembled operating relation by means of centering and clamping actions of a heavy nonmagnetic centering disc but with the aid of a plurality of bolts which clamp the pole plate to the centering disc and the latter to the yoke. Such an arrangement, although a worthwhile improvement over the art, is somewhat complicated and expensive. In this modification the magnet 53 is a small cylindrical block of "Alnico V" an alloy of much higher magnetic energy than the older forms of Alnico, an alloy composed of aluminum 8%, nickel 14%, cobalt 24%, copper 3% and the rest iron. Because of the characteristics of the material, and high magnetic energy storage in a small lightweight piece, the present clamping system is ideally suitable. It has been found undesirable to provide a bore hole in the magnet for bolting purposes. It had been the custom in making the heavier and larger magnets of ordinary Alnico alloy to provide a

central bore hole at the time of molding, for bolting parts together, as shown in Cunningham Patent 2,312,238 of February 23, 1943, but such an arrangement had been found undesirable with the new alloy magnets.

In accordance with the present invention a yoke plate 41, Figure 4, preferably rectangular, is welded to the ends of a U-shaped yoke 43. The bottom face of plate 41 is provided with a milled groove 42, concentric with opening 13, into which fits the upper edge of a dished circular centering element 45, preferably of phosphor-bronze, the groove securing the centering element against lateral movement. This element is provided with a central opening 47 accurately concentric with respect to opening 13 in the pole plate 41 and is normally biased downward in the same manner as shown in Figure 1. Element 45 is preferably slit radially as shown at 46 in Figure 4a, to provide a plurality of independently biased spring segments to provide greater spring action and more circumferentially uniform pressure around flange 51. A pole piece 49, provided with a lower annular flange 51, is assembled into approximately the position shown by laterally inserting same relative to the yoke 43 and upwardly into the position concentric with respect to and spaced from the opening 13 to form an air gap. Clamping tools are used during assembly to force the pole piece 49 and spring element 45 upwardly slightly beyond the position shown and holding them in such position while the magnet 53 is inserted laterally into the position shown. The base of magnet 53 preferably fits into a slight depression 54 formed by milling or pressing, to insure against lateral displacement in the case of severe shocks, as from dropping the unit. It will be apparent, therefore, that this modification results in a substantial simplification and improvement.

Referring to Figure 5, a disc 55 is used for centering the pole pieces and a separate spring clamp 57 is used for pressing the magnetic elements together, as shown and claimed broadly in combination in Cunningham application Serial No. 632,064, filed concurrently herewith. In this modification, however, each end of the spring clamp 57 is biased upwardly and outwardly, as shown in dotted lines, and when assembled, engages an abutment or offset shoulder 59 with a high degree of compression, holding the elements firmly together as shown. The assembly is accomplished simply by inserting the elements 49, 57 and subsequently 53, with the spring tension relieved as in the position shown in dotted lines. Then figures of an arbor press are inserted to press the spring arms 57 downward until the ends snap into position against shoulder 59. In this modification, the assembly of the pole piece 49 and magnet 53 onto yoke 43 is substantially independent of the pole plate 41 and devices carried thereon, and if desired the latter can subsequently be dropped into position with the centering disc fastened in place, and welded in the position shown. It is ordinarily advantageous to weld the pole plate in position first but there are cases where the reverse is desired.

Another feature of the Figure 5 modification is that several portions of the spring 57 are bent downwardly below flange 51 and annularly spaced closely around the top of the magnet 53 below the upper polar face for the purpose of limiting any lateral displacement of the magnet 53, as in Figure 3. This avoids the use of a depression (Fig. 4) or other means on the yoke around the base of the magnet, or the use of a separate element as

in Figure 3. Ordinarily bolts, lugs, cement are used to anchor the magnet to prevent shifting, and in some cases the space between the magnet and yoke has been filled in with plastic molding material to hold all members together in a mass. With the present improvement, the portion of the field yoke in contact with the magnet base may be ground to provide a smooth flat surface without any obstructions for ease of lateral assembly and providing an efficient contact area with the lower polar face of the magnet.

In Figure 6 the centering disc 60 is made of relatively stiff nonmagnetic material, is fastened permanently to plate 41, as by welding, and the inner opening counterbored concentrically relative to yoke plate opening 13, fits snugly around inner pole piece 49. The resilient pressure effect is obtained in part or in entirety by separate means such as a soft rubber ring 58 held in compression between the inner portion of the disc and the shoulder 51 on the base of the inner pole piece 49. Limitation of lateral movement of the magnet 53 is effected by lancing out several tongues 56, say four spaced ninety degrees apart, radially from the disc and bending them partway downward, as shown in dotted lines, in radially spaced relation. After assembling the magnet, the tongues are bent all the way down around the upper end of the magnet, as shown. The disc, therefore, serves for accurately centering the pole piece 49 concentrically with respect to the opening 13 in the plate 41, for approximately centering the magnet, and cooperates with resilient means 58 for resiliently clamping the members 49 and 53 together and in place on the yoke, not shown, but similar in general to that of Figure 5. Similar lateral limiting structure may be formed in disc 15 of Figures 1, 2 or 4. Alternatively, rubber ring 58 may be discarded, and the centering disc engage the shoulder 51, relying on the resiliency of the disc 60 to clamp the magnetic members axially, as in Figure 1. In Figure 6 the disc, with or without the rubber ring, may be termed resilient centering means having structure for limiting lateral displacement of said magnet.

While the embodiments of the present invention as herein disclosed constitute preferred forms, it is to be understood that other forms might be adopted within the scope of the present invention and within the scope of the claims which follow. While the invention has been illustrated in connection with a permanent magnet speaker, it will be found to have patentable utility with a field winding speaker.

I claim as my invention:

1. A dynamic loudspeaker comprising in combination (1) a field structure including a field yoke and a yoke plate connected to said field yoke, said yoke plate having a centrally disposed circular opening, (2) a magnet having upper and lower pole faces with said lower pole face disposed on said field yoke, (3) a pole piece having one end thereof disposed upon said upper pole face, said pole piece having its opposite end extending into said opening in spaced relation to said yoke plate thereby to provide an air gap therebetween, and (4) an annular, disc-like spring secured to said yoke plate, said spring embracing and engaging said pole piece to center it in said yoke plate opening, said spring being biased by engagement thereof with said pole piece in a direction such as to cause it to exert a force against said pole piece in an axial direction toward said magnet whereby said spring is effective to maintain said pole piece,

55 said magnet and said field structure in assembled relation.

2. The invention set forth in claim 1 wherein said pole piece has an annular shoulder against which said spring exerts its force for securely holding said pole piece, said magnet and said field structure in assembled relation.

3. In a dynamic loudspeaker, a U-shaped field yoke of magnetic material having a base portion including a pole face intermediate the ends of said yoke, a yoke plate attached to said ends and provided with a circular opening, a permanent magnet having one end disposed upon said field yoke pole face, a pole piece having a lower pole face disposed upon the opposite end of said magnet and provided with an annular shoulder, spring means attached to said yoke plate and provided with an opening concentrically located with respect to said yoke plate opening, said spring means being of non-magnetic material and surrounding and engaging said pole piece for centering said pole piece within said yoke plate opening, said spring means being in contact with said annular shoulder and being biased by engagement thereof with said shoulder in a direction such as to cause it to exert a force against said shoulder in an axial direction toward said magnet whereby said spring means is effective to securely hold said pole piece, said magnet and said yoke in assembled relation.

4. A dynamic loudspeaker comprising, in combination, (1) a field structure including a field yoke and a yoke plate connected to said field yoke, said yoke plate having a centrally disposed circular opening, (2) a magnet having upper and lower pole faces with said lower pole face disposed on said field yoke, (3) a pole piece having one end thereof disposed upon said upper pole face, said pole piece having its opposite end extending into said opening in spaced relation to said yoke plate thereby to provide an air gap therebetween, and (4) a sheet metal centering spring secured to said yoke plate, said spring embracing and engaging said pole piece to center it in said yoke plate opening, said spring being biased by engagement thereof with said pole piece in a direction such as to cause it to exert a force against said pole piece in an axial direction toward said magnet whereby said spring is effective to maintain said pole piece, said magnet and said field structure in assembled relation.
